(No. Model.)

Z. T. FRENCH & W. C. MEYER.
WELT SEAM TRIMMING MACHINE.

No. 558,381.

Patented Apr. 14, 1896.

UNITED STATES PATENT OFFICE.

ZACHARY T. FRENCH AND WILLIAM C. MEYER, OF BOSTON, MASSACHUSETTS.

WELT-SEAM-TRIMMING MACHINE.

SPECIFICATION forming part of Letters Patent No. 558,381, dated April 14, 1896.

Application filed June 14, 1895. Renewed March 26, 1896. Serial No. 584,936. (No model.)

To all whom it may concern:

Be it known that we, ZACHARY T. FRENCH and WILLIAM C. MEYER, of Boston, county of Suffolk, and State of Massachusetts, have invented an Improvement in Welt-Seam-Trimming Machines, of which the following description, in connection with the accompanying drawings, is a specification, like letters and figures on the drawings representing like parts.

This invention has for its object to improve and simplify the construction of machines for trimming the welt-seams of welted boots and shoes, so as to present a smooth flat surface for the outer sole, and at the same time materially increase the capacity of the machine.

Our invention comprehends an oscillating or vibrating trimming-knife sharpened upon one side, and preferably arranged to trim the welt-seam on both the up and down movements thereof; and our invention consists, furthermore, in the combination, with such an oscillating or vibrating trimming-knife, of feeding mechanism adapted to intermittently feed along the work, and acting to feed the work each time the trimming-knife cuts; also, in the combination, with such an oscillating or vibrating trimming-knife, of feeding mechanism to feed along the work intermittently each time the trimming-knife cuts, and a work-support against which the work is held pressed by the operator.

The feeding mechanism may comprise a pair of feeding-jaws, with means for operating them to grip the welt, then feed along the work, then release their hold upon the welt and return to their normal position to obtain another grip upon the welt.

The front jaw of the pair of feeding-jaws will be so shaped as to enter and work close to or in the inseam or crease or bear upon the last adjacent thereto, and the rear jaw of the pair of feeding-jaws will be so constructed as to afford ample space for the welt-seam-trimming knife to work.

The work-support may be made in many ways; but a simple loop-like structure having a thin or more or less tapered end which enters the inseam or crease or bears against the last adjacent thereto will effectually subserve the purpose, the end of the loop being

made wide enough to cover or bear upon several of the stitches to equalize the pressure and prevent straining the stitches.

55

Figure 1 shows a right-hand side elevation of a welt-seam-trimming machine embodying this invention; Fig. 2, a front elevation of the same; Fig. 3, a sectional detail of the feeding-jaws on the dotted line z ; Fig. 1; Fig. 4, a rear side view of the rear jaw; Fig. 5, a cross-section of the welt-seam-trimming knife.

The framework comprises, essentially, a base A and two vertical side pieces B B, rising therefrom. The main shaft a is journaled in said pieces B and has secured to it an eccentric disk a' , (see dotted lines, Fig. 1,) embraced by an eccentric strap a'' , from which projects outwardly an arm a''' , the lower end of which is connected by a pin 2 or otherwise with a knife-carrying arm a^4 , pivoted at a^5 to a block C, dovetailed in the base A and secured thereto in an adjustable manner, as by a screw 3, passing through a slot and entering the base. The knife-carrying arm a^4 has secured to its extremity a curved trimming-knife b, one edge of which is sharpened. As the main shaft a revolves the knife-carrying arm a^4 is vibrated and the trimming-knife b thereby oscillated in the arc of a circle of which the pivot a^5 is the center. This form of welt-seam-trimming knife will cut off the "between substance" or trim the welt-seam during both the ascent and descent thereof, thereby greatly increasing the capacity of the machine.

The lasted boot or shoe to which a welt has been sewed is held up against a suitable work-support c, herein shown as a loop secured to a yoke or frame c', attached to the base A in an adjustable manner, as by screws 4, passing through slots and entering the base. The lower end of the loop c is made quite thin—as, for instance, it may be more or less tapered—so as to enter the inseam or crease or bear against the upper drawn taut over the last at a point adjacent the welt. The acting end of the loop c is made quite wide, so as to overlie several stitches to equalize the pressure and prevent straining the stitches.

Instead of making the work-support c as a loop-like structure, it may be made in many different ways to present a thin acting end,

which is required to work down close in the inseam or crease.

As a feeding mechanism we have herein shown a clamp feeding device, constructed and arranged to intermittently feed along the work. The clamp feeding device shown consists of a pair of jaws d e , the lower ends of which are made thin and tapering, so that the front jaw may work close in the inseam or crease and the rear jaw afford ample space for the trimming-knife to work, and said jaws are adapted to close together and grip and hold between them the welt and then carry the boot or shoe along a short distance, then open, releasing the welt and thereafter return to their starting-point. Such form of clamp feeding device is frequently called a "four-motion" feeding device.

The jaw d is located within the loop-like work-support c and works back and forth between the vertical arms or sides thereof. This jaw d is attached by screws 5 to an arm d' , depending from a sleeve d^2 , mounted on a rod d^3 , said sleeve being free to rock and also slide longitudinally on said rod. The screws 5 pass through slots in said arm d' to enable the jaw d to be adjusted in and out, and a limiting-stop passes through an ear on the arm d' , bearing against the front of said jaw. Two arms project radially from the sleeve d^2 , one, as d^4 , bearing a pin d^5 , which enters a cam-groove formed in the side of the disk D , secured to the main shaft a , said groove being so shaped that as the disk revolves the sleeve d^2 will be rocked axially on the rod d^3 , each revolution of said disk so rocking the sleeve to and fro twice. The other radially-projecting arm d^6 (see dotted lines, Fig. 1) enters a peripheral cam-groove in said disk, said groove being so shaped as to cause the sleeve d^2 to reciprocate longitudinally on the rod d^3 , each revolution of said disk so moving the sleeve back and forth longitudinally twice, and the parts are so timed that the sleeve d^2 will be first rocked in one direction, moving out the jaw d , then moved on the rod d^3 in a direction toward the right, carrying the jaw d with it, then rocked in the opposite direction, moving the jaw d inward that it may engage the welt, then move on the rod in a direction toward the left to feed along the work, thereby giving to the jaw d four motions. These four motions will occur during each half-revolution of the disk D , and either immediately before or after the welt-seam-trimming knife has descended and ascended. The jaw e is attached by screws 7 to an arm e' , depending from a sleeve e^2 , mounted on a reduced portion of the sleeve d^2 . (See Fig. 2.) One end of the sleeve e^2 bears against a shoulder formed on the sleeve d^2 and the other end bears against a collar e^3 , secured to the projecting end of the sleeve d^2 . By this construction the sleeve e^2 is caused to reciprocate longitudinally with the sleeve d^2 , yet is permitted to rock axially independently. An arm e^4 projects radially from the sleeve e^2 , bearing a pin e^5 , which enters a cam-groove

formed in the face of a disk D' , secured to the main shaft a , said cam-groove being so shaped as to rock the sleeve e^2 substantially at the same time that the sleeve d^2 is rocked, but in the opposite direction, so that the jaw e will be moved away from the work at the same time that the jaw d is moved away.

It may be necessary to only give one of the jaws four motions, the other jaw moving only back and forth, and in such case we prefer to give the front jaw d four motions and the rear jaw e two motions, and in such event the cam-grooved disk D' and arm e^4 with its pin e^5 may be omitted, or said parts may be utilized for the purpose of steadyng the jaw, and the groove in the disk in such case being made truly circular. The jaw e is cut away upon its rear side to afford ample space for the oscillating trimming-knife b . This form or construction of feeding mechanism, it will be observed, works close to the inseam or crease and enables the operator to hold the work at the proper angle, that the seam may be trimmed close to the stitches, and obviating the necessity of tilting the shoe in such manner as is required when using a roller-feed.

In operating the machine the boot or shoe is held up against the work-support c , and as the shaft a revolves the jaws d e grasp the welt and intermittently feed along the shoe and the trimming-knife oscillates and trims off the between substance, the work being fed along two steps to each revolution of the main shaft a and the welt-seam-trimming knife cutting the seam both as it descends and also as it ascends.

We do not herein broadly claim a welt-seam-trimming knife turning on an axis and means for holding and feeding the work having as a co-operative part of it a device which acts upon the under side of the welt and projects inwardly and terminates close to the point where the cutting is being done, thereby entering the gradually-contracted space between said knife and welt tangent to the curvature of the knife and holding the work directly opposite where the cutting is being done, as such feature is claimed in our application Serial No. 576,925.

We claim—

1. In a welt-seam-trimming machine, the combination of a work-support at the face side of the welt, a welt-seam-trimming knife at the opposite side thereof having a cutting edge upon one side, means for moving it, a pair of clamp feeding-jaws, and means for operating them to grip the welt, and to feed along the work against the cutting edge of the moving knife, substantially as described.

2. In a welt-seam-trimming machine, the combination of a work-support at the face side of the welt, a welt-seam-trimming knife at the opposite side thereof having a cutting edge upon one side, means for moving it, a pair of clamp feeding-jaws, and means for operating them to grip the welt, and feed along the work against the cutting edge of

558,381

the moving knife, the knife moving in a curved path close to the work-support and coöperating therewith to hold the work while the feeding-jaws return, substantially as described.

3. In a welt-seam-trimming machine, the combination of a pair of clamp feeding-jaws, means for operating them to grip the welt and feed along the work, a work-support at the face side of the welt, and a welt-seam-trimming knife at the opposite side of the welt having a cutting edge upon one side, the feeding-jaws feeding along the work during the

ascent and descent of the knife, and the knife while in its two extreme positions coöperating with the work-support to hold the work ¹⁵ while the feeding-jaws return, substantially as described.

In testimony whereof we have signed our names to this specification in the presence of ²⁰ two subscribing witnesses.
